(57) **CLAIM**

The ornamental design for a spoon, as shown.

DESCRIPTION

The spoon-Z is a two-headed spoon with a handle in the middle. The scoop heads are angled in opposite directions. It has higher scoop walls than an ordinary spoon to prevent spillage. It also has three raised ridges on each scoop head to help grip food.

FIG. 1 is a top view of a spoon showing my new design;

FIG. 2 is a front view;

FIG. 3 is a left side view;

FIG. 4 is a rear view;

FIG. 5 is an enlarged partial view of the spoon bowl;

FIG. 6 is a bottom view;

FIG. 7 is a top view of a second embodiment;

FIG. 8 is a bottom view of FIG. 7;

FIG. 9 is a front view of FIG. 7; and,

FIG. 10 is a top perspective view of FIG. 7.
